(57) **CLAIM**

We claim the ornamental design for a tape dispenser, as shown and described.

DESCRIPTION

FIG. 1 is a front view of the tape dispenser;
FIG. 2 is a back view of the tape dispenser;
FIG. 3 is a left side view of the tape dispenser;
FIG. 4 is a right side view of the tape dispenser;
FIG. 5 is a top view of the tape dispenser;
FIG. 6 is a bottom view of the tape dispenser;
FIG. 7 is a perspective view of the tape dispenser; and,
FIG. 8 is a perspective view of the tape dispenser positioned on a tape roll.
The broken lines shown in the FIG. 6 represents environmental structure that forms no part of the claimed design.
